US00D917815S

(12) **United States Design Patent** (10) Patent No.: **US D917,815 S**
(45) Date of Patent: **** Apr. 27, 2021**

(54) **WATER TANK FOR ROBOTIC VACUUM CLEANER**

(71) Applicant: **LG ELECTRONICS INC.**, Seoul (KR)

(72) Inventors: **Seongmin Kim**, Seoul (KR); **Seunghyun Song**, Seoul (KR); **Hoil Jeon**, Seoul (KR)

(73) Assignee: **LG Electronics Inc.**, Seoul (KR)

(**) Term: **15 Years**

(21) Appl. No.: **35/508,477**

(22) Filed: **Jul. 29, 2019**

(80) **Hague Agreement Data**

Int. Filing Date: **Jul. 29, 2019**

Int. Reg. No.: **DM/204193**

Int. Reg. Date: **Jul. 29, 2019**

Int. Reg. Pub. Date: **Jan. 31, 2020**

(57) **CLAIM**

The ornamental design for a water tank for robotic vacuum cleaner, as shown and described.

DESCRIPTION

1. Water tank for robotic vacuum cleaner

1.1 : Perspective

1.2 : Rear perspective view

1.3 : Front

1.4 : Back

1.5 : Left

1.6 : Right

1.7 : Top

1.8 : Bottom

1.9 : Reference

The article has transparent materials.
